(57) **CLAIM**

The ornamental design for a child ride-on bike, as shown and described.

DESCRIPTION

The patent or application file contains at least one drawing executed in color, of which forms part of the claimed design. Copies of this patent or patent application publication with color drawing(s) will be provided by the Office upon request and payment of the necessary fee.

1.-2. CHILD RIDE-ON BIKE

1.1 is a left side elevation view of a child ride-on bike showing our new design in accordance to a first embodiment;

1.2 is a right side elevation view thereof;

1.3 is a front elevation view thereof;

1.4 is a rear elevation view thereof;

1.5 is a top plan view thereof;

1.6 is a bottom plan view thereof; and

1.7 is a front perspective view thereof.

2.1 is a left side elevation view of a child ride-on bike showing our new design in accordance to a second embodiment;

2.2 is a right side elevation view thereof;

2.3 is a front elevation view thereof;

2.4 is a rear elevation view thereof;

2.5 is a top plan view thereof;

2.6 is a bottom plan view thereof; and

2.7 is a front perspective view thereof.
